United States Patent Office

Des. 196,201
Patented Sept. 3, 1963

196,201

MOTION PICTURE CAMERA

Frederick Hertzler, St. Clair Shores, Mich., assignor, by mesne assignments, to Argus Incorporated, a corporation of Delaware

Filed Nov. 28, 1961, Ser. No. 67,724

Term of patent 3½ years

(Cl. D61—1)

FIG. 1

Des. 196,201

I claim:

The ornamental design for a motion picture camera, substantially as shown.
